UNITED STATES PATENT OFFICE.

CARL H. WALLES, OF CHICAGO, ILLINOIS.

TOWING-LINE.

1,371,335.

Specification of Letters Patent. Patented Mar. 15, 1921.

Application filed January 12, 1920. Serial No. 350,806.

To all whom it may concern:

Be it known that I, CARL H. WALLES, a citizen of the United States, residing at Chicago, in the county of Cook and State 5 of Illinois, have invented new and useful Improvements in Towing-Lines, of which the following is a specification.

This invention relates to improvements in tow lines and refers more particularly to 10 resilient connections for automobile tow lines.

The principal object of the invention is to provide a simple and efficient tow line having improved means for removably attaching 15 the tow line to the axle of an automobile, and having resilient means carried thereby to resist the usual tendency of such a line to break when the load is suddenly applied.

With the foregoing object in view, this 20 invention comprises the new and useful details of construction and arrangement, which will be fully described herein, illustrated in the annexed drawings, and claimed more 25 specifically hereinafter.

In the drawings:

Figure 1 is an elevation of a portion of the improved tow line;

Fig. 2 is an enlarged fragmentary section 30 of the resilient anchoring means;

Fig. 3 is a detail perspective view of the anchoring loop and abutment washer;

Fig. 4 is a detail plan view of the anchoring means, shown partly in section.

Referring now to the drawings, it will be 35 seen that the improved tow line comprises a cable 5 having its end doubled and formed into a loop 6 in which is carried a connecting hook 7. The end of the cable is engaged securely at 9 to the tow line in any suitable manner, as by wrapping. The doubled end of the cable is preferably provided with a tubular fabric cover or sheath 10, which for the purpose of the present 40 embodiment may be a length of hose positioned to prevent the tow line from rubbing the axle 11 of the automobile when in place thereon. Adjacent to the inner end of the covered section 10 is a clip 12 of any suitable type adapted to clamp the hose securely to the cable. An abutment in the 45 form of a washer 13 is carried on the cable against clip 12, a central perforation 14 through the washer allowing the washer to

be slipped in place on the doubled cable 55 end. Washer 13 is provided at diametrically opposite points on its periphery with notches 15, and an elongated U-shaped anchoring loop 16 is sprung in place therein, the ends of the loop being turned inwardly 60 and then forward to form stops 17, for a purpose to be presently explained. Another abutment washer 19 is positioned within the seat formed by the inturned stops 17, the washer being centrally perforated to receive 65 the stops and tow line in an obvious manner. A coil spring 18 is carried about the tow line with one end thereof seated against abutment 13, the other end being seated against abutment 19, the diameter of the 70 spring being less than the distance between the loop members so that the spring will clear the loop. The stops are adapted to enter the coils of the spring, as will be clearly seen by reference to Fig. 4. 75

In use, the doubled end of the cable is adapted to be looped above the axle 11 of the automobile, as previously pointed out, and the hook 7 engaged in the end of anchoring loop 16. It will be apparent that 80 when the cable is drawn tight, the weight of the load will form a straight line pull on hook 7 and anchoring loop 16, the spring 18 resisting the tendency of the loop to slide forward on washer 13. When the load is sufficient to compress spring 18, the loop will then 85 slide on the washer until the stops 17 contact with the washer 13, whereupon the pull will be direct on the cable and anchoring loop, the clip 12 preventing the washer from 90 sliding on the cable. It will also be seen that when the tow line is subjected to a jerk, the shock of such a pull will be absorbed by the action of spring 18, relieving the cable of the usual tendency to break. 95

From the foregoing description, it will be readily seen that this invention provides an improved connection for tow lines having resilient means for absorbing the shock when the load is applied thereto suddenly. 100

The invention is shown applied to a tow line, but it will be understood that it may also be used in connection with hauling lines of any kind, elevator cables, hoisting lines, etc. 105

I claim:

1. The combination with a tow line, of a resilient anchoring device attached to said

line back of its terminal, and means for detachably connecting the end of the line to said device.

2. A resilient anchoring means comprising a supporting member, an abutment on the supporting member, a loop slidable relative to the abutment and having inturned and forwardly extending rear ends, and a

coil spring between the abutment and the inturned ends of the loop, the aforesaid forwardly extending portions being positioned to be intercepted by the abutment to limit the forward movement of the loop. 10

In testimony whereof I affix my signature.

CARL H. WALLES.
